DESIGN FOR AN ICE CREAM CONE

James C. Pecora, West Hazleton, Pa.

Application November 29, 1938, Serial No. 81,459

Term of patent 7 years

To all whom it may concern:

Be it known that I, James C. Pecora, citizen of the United States and resident of West Hazleton, county of Luzerne, and State of Pennsylvania, have invented a new, original, and ornamental Design for Ice Cream Cones, of which the following is a specification, reference being had to the accompanying drawing, forming a part thereof.

Fig. 1 is a front view of the ice cream cone showing my new design.

Fig. 2 is a side view thereof.

Fig. 3 is a plan view thereof.

The characteristic features of my design reside in the pair of heart-shaped elements disposed around the open end of the cone, each of said heart-shaped elements being ornamented by a pair of smaller hearts pierced by an arrow as shown.

I claim:

The ornamental design for an ice cream cone, as shown and described.

JAMES C. PECORA.
